UNITED STATES PATENT OFFICE.

ROBERT W. MACKINTOSH, OF BUFFALO, NEW YORK, ASSIGNOR TO M. H. BIRGE & SONS COMPANY, OF BUFFALO, NEW YORK, A CORPORATION.

DESIGN FOR WALL-PAPER.

42,638.

Specification for Design.

Patented June 18, 1912.

Application filed April 24, 1912. Serial No. 692,988. Term of patent 7 years.

To all whom it may concern:

Be it known that I, ROBERT W. MACKINTOSH, a citizen of the United States, residing at Buffalo, in the county of Erie and State of New York, have invented a new, original, and ornamental Design for Wall-Paper, of which the following is a specification.

The accompanying drawing represents a section or piece of wall paper embodying the design.

I claim:

The ornamental design for wall paper, as shown.

ROBERT W. MACKINTOSH.
